COIN CHANGER

Guy M. Farrell, Chicago, Ill., assignor, by mesne assignments, to Brandt Automatic Cashier Company, a corporation of Wisconsin

Application October 28, 1957, Serial No. 692,613

4 Claims. (Cl. 133—2)

This invention relates to a coin changer such as one of the type shown in the co-pending application of Allan E. Finke and Edgar M. Katzenberg, Serial No. 486,326, filed February 7, 1955, and is directed particularly to a means for delivering change from 25¢, 50¢ or 75¢ as distinguished from the usual arrangement of dispensing change from \$1.00.

One object of the invention is to provide a comparatively simple relay and push button arrangement that can be added to the type of machine shown in the Finke and Katzenberg application, together with an electrical operating circuit therefor, and which is operable in addition to the normal operation of depressing denomination buttons by selecting and depressing a push button to deliver change from 25¢, 50¢ or 75¢ as desired.

Another object is to provide means to dispense the change from 50¢ for instance instead of \$1.00 by merely disabling the coin ejecting mechanism for the 50¢ pieces in the machine and likewise to provide another means for disabling both the 50¢ ejector and the 25¢ ejector if it is desirable to dispense change from either 25¢ or 75¢.

Still another object is to provide relays which are energized by selector push buttons and which are provided with switches for controlling relays that disable certain actuating solenoids of the coin changer, holding switches being provided to retain the relay coils energized once they are energized whereupon a subsequent coin changer operation dispenses the change from 25¢, 50¢ or 75¢ whichever is selected.

A further object is to provide a passing switch operated by any one of the coin ejectors for opening the circuit of one of these relays that has been energized so as to recondition the coin changer for \$1.00 operation, and to provide indicator lights associated with the relays to indicate their energization and de-energization, thus warning the operator of the condition of the circuit at any time so that he knows upon operation of the coin changer whether it will make change from 25¢, 50¢, 75¢ or \$1.00.

With these and other objects in view, my invention consists in the construction, arrangement and combination of the various parts of my coin changer whereby the objects above contemplated are attained, as hereinafter more fully set forth, pointed out in my claims and illustrated in detail on the accompanying drawings, wherein:

Fig. 1 is a cross-sectional view through a portion of a coin changer such as shown in the above-mentioned application to show the actuating mechanism thereof and illustrating a portion of my invention applied thereto;

Fig. 2 is a circuit diagram illustrating my invention; and

Fig. 3 is a sectional view on the line 3—3 of Fig. 1 showing a passing switch used in connection with my invention.

On the accompanying drawing I have used the reference numeral 12 to indicate a coin changer housing and adjacent the top thereof is a coin tray 14 for stacks of coins from pennies to half dollars. Two coins 50 are illustrated in one channel of the coin tray 14 and a third coin (also

2

50) is being ejected therefrom. The reference numeral 50 in this case indicates a 50¢ coin.

Ejection of the coins is effected by coin ejector bars 16 pivoted to bell cranks 18 which are oscillatably mounted on a pivot shaft 20 supported by brackets 22. Cores 26 are pivoted to bell cranks 18 and enter solenoids 24 which when energized draw the cores inward with respect to the solenoids and thereby rock the bell cranks. Return springs 28 are provided for the bell cranks 18. In Fig. 1 the vertical solenoid 24 is shown energized and its bell crank rocked counterclockwise whereas the horizontal solenoid 24 is de-energized and its bell crank has been rocked clockwise by its return spring 28.

In Fig. 2 the solenoids 24 for the 50¢ pieces, the 25¢ pieces and for "Others" are indicated and there are also solenoid switches 30 for the three 24(50), 24(25) and 24(Others) solenoids just mentioned. The "Others" may be for instance two 10¢ solenoids, one 5¢ solenoid, two 2¢ solenoids and one 1¢ solenoid. The last 2¢ solenoids dispense two pennies at a time and the arrangement just enumerated has been found in most instances the most satisfactory for substantially equal depletion of the stacks of coins in the coin tray 14. The switches 30 are closed in various combinations to eject desired denominations of coins when making change from \$1.00.

In Fig. 2, I illustrate a wiring diagram in which the solenoids 24 and the switches 30 are connected in an operating circuit, and current supply wires 46 and 48 may be suitably charged as from a rectifier 25 shown in Fig. 1. The lower ends of the wires 46 and 48 in Fig. 2 terminate in arrow heads to represent extension of the circuit to the additional solenoids 24 and switches 30 included under "Others." The ordinary coin changer for making change from \$1.00 includes the elements 24 and 30 just referred to in the circuit shown with the exception of circuit opening switches S³, S⁴, and S⁵ which are part of my invention. I will now describe the remaining elements of my invention which are added to the coin changer to make it possible to selectively make change from denominations of 25¢, 50¢ and 75¢.

I provide relays having coils R¹ and R² and manual selector switches S¹ and S² for controlling the relays. The relay having the coil R¹ includes the switches S³ and S⁵ and a holding switch 32 whereas the relay having the coil R² includes the switch S⁴ and a holding switch 34. R¹ when energized opens the normally closed switches S³ and S⁵ and closes the normally open switch 32 whereas energization of R² opens the normally closed switch S⁴ and closes the normally open switch 34.

A passing switch 36 is normally closed and controls all circuits through R¹ and R² and through indicator lights L¹ and L² therefor. The holding switches 32 and 34 shunt the switches S¹ and S² whereby momentary closure of S¹ or S² will effect closure of 32 or 34 respectively, thus holding the circuit for the relay that has been energized by S¹ or S² until such time as the passing switch 36 is opened. Resistors 44 may be included in the circuits of the relay coils R¹ and R² to reduce the current flow therethrough inasmuch as these coils do not require much current for their operation as do the solenoids 24. The indicator lights L¹ and L² serve to indicate that either the switch S¹ or the switch S² has been depressed and likewise upon extinguishment due to opening of the passing switch 36 indicate their subsequent de-energization.

Practical operation

When the coin changer is operated in the normal manner (for change from \$1.00) neither of the manual selector switches S¹ or S² is depressed. If it is desirable to make change from 50¢, however, S² is depressed where-

upon the relay coil R^3 is energized which closes the holding switch 34 so that S^2 can be released and the coil will remain energized, and the circuit opening switch S^4 is opened so that the solenoid 24(50) cannot operate. The light L^2 is energized to indicate that the circuit is ready for making the change from 50¢. The operator then presses the appropriate denomination key of the controlling keyboard (such as 40 if the purchase was 40¢) and the solenoid 24 for a 10¢ coin channel is thereby energized by the closure of its switch 30 to eject a 10¢ piece as change. Also, the switch 30 for a 50¢ coin will be depressed but since S^4 is open, only the solenoid 24 for the 10¢ piece will not be energized to eject only 10¢ change instead of 50¢ plus 10¢ or 60¢ change from \$1.00.

Referring to Fig. 3, the passing switch 36 is illustrated in detail. It has an upward projection 38 to be actuated by a downward projection 42 from a passing switch actuator in the form of a bell crank 39, longitudinal part 40 shown sectioned in Fig. 1 and a vertical arm 42 which is shown sectioned in Fig. 3. The bell crank 39 rocks on the pivot shaft 20 and a return spring 41 is operable to normally rotate the passing switch actuator 39—40—42 clockwise in Fig. 1. It has been actuated counterclockwise by the nearest bell crank 18 and this results in the projection 42 passing the projection 38 and bending the switch 36 upwardly in Fig. 3 without opening the circuit. However, when the projection 42 moves in the opposite direction it will so engage the projection 38 as to open the switch 36 in an obvious manner and then permit it to re-close before the actuator 39—40—42 returns to its initial position against a stop 43 under the action of the spring 41.

When the passing switch 36 opens, the relay coil R^2 and the indicator light L^2 are de-energized and the circuit is conditioned for subsequent normal operation—that is, making change from \$1.00.

In the event that change is to be made from either 25¢ or 75¢ the switch S^1 is manually closed for energizing the relay coil R^1 which opens switches S^3 and S^5 in both the 50¢ and 25¢ solenoid circuits. Thus neither of the 50¢ or 25¢ coin ejectors will operate when their respective switches 30 are closed because of the normal operation of the coin changer—that is, the depression of 15¢ for instance if that is the sale, whereupon the solenoid for the 10¢ ejector only will operate. Likewise the 10¢ ejector only will operate if 65¢ is rung up on the coin changer for a 65¢ purchase from 75¢ paid. Thus the switch S^1 is used for making change from either 25¢ or 75¢ and only two of the selector switches S^1 and S^2 thus need be provided to adapt a \$1.00 coin changer to make change from any of 25¢, 50¢ or 75¢.

Again the passing switch 36 will open upon the return of the coin ejector or ejectors to normal positions after de-energization of the relay R^1 and the indicator light L^1 , thus conditioning the circuit for subsequent \$1.00 operation again.

From the foregoing specification it will be obvious that I have provided a comparatively simple relay and selector switch arrangement with only three circuit connections (switches S^3 , S^4 and S^5) into the normal \$1.00 coin changer to adapt it for 25¢, 50¢ and 75¢ operation also. The relays and switches as well as the indicator lights L^1 and L^2 and the passing switch 36 are relatively small so that they can be mounted in the coin changer housing and the housing for the denomination push button assembly that operates the coin changer without interfering with any of the mechanism.

Some changes may be made in the construction and arrangement of the parts of my coin changer without departing from the real spirit and purpose of my invention, and it is my intention to cover by my claims any modified forms of structure or use of mechanical equivalents which may reasonably be included within their scope.

I claim as my invention:

1. In a coin changer adapted to make change from one denomination and including ejecting circuits for coins of various lesser denominations, means to selectively disable certain of said ejecting circuits whereby to make change from smaller denominations than said one denomination comprising relays having coils and switches, manual selector switches for selectively energizing said relay coils, one switch of each relay coil comprising a holding switch for the circuit of the coil, the other switches thereof being normally closed and located in those ejecting circuits which represent the difference between said one denomination and said smaller denomination, and a passing switch in circuit with said relay coils to de-energize them as the coin changer returns to idle position.
2. In a coin changer adapted to make change from one denomination and including ejecting circuits for coins of various lesser denominations, means to selectively disable certain of said ejecting circuits whereby to make change from smaller denominations than said one denomination comprising relays having coils and switches, manual selector switches for selectively energizing said relay coils, one switch of each relay coil comprising a holding switch for the circuit of the coil, the other switches thereof being normally closed and located in those ejecting circuits which represent the difference between said one denomination and said smaller denomination, a passing switch in circuit with said relay coils to de-energize them as the coin changer returns to idle position, and indicator lights for said relays to indicate their energization and de-energization.
3. In a coin changer adapted to make change from one denomination and including ejector circuits for coins of various lesser denominations, means to disable certain of said ejecting circuits whereby to make change from a smaller denomination than said one denomination comprising a relay having a coil and switches, manually operable means for energizing said relay coil, one switch of the relay coil comprising a holding switch for the circuit of the coil and another switch thereof being normally closed and located in that ejecting circuit which represents the difference between said one denomination and said smaller denomination, a passing switch in circuit with said relay coil to de-energize it as the coin changer returns to idle position after a coin changing operation, and an indicator light for said relay to indicate its energization and de-energization.
4. In a coin changer adapted to make change from one denomination and including ejector circuits for coins of various lesser denominations, means to disable certain of said ejecting circuits whereby to make change from a smaller denomination than said one denomination comprising a relay having a coil and switches, manually operable means for energizing said relay coil, one switch of the relay coil comprising a holding switch for the circuit of the coil and another switch thereof being normally closed and located in that ejecting circuit which represents the difference between said one denomination and said smaller denomination, and a passing switch in circuit with said relay coil to de-energize it as the coin changer returns to idle position after a coin changing operation.
